UNITED STATES PATENT OFFICE.

MATTHEW L. KING, OF BRADLEY, ILLINOIS.

SILO-DOOR FRAME.

1,249,970.

Specification of Letters Patent. Patented Dec. 11, 1917.

Application filed January 21, 1915. Serial No. 3,637.

To all whom it may concern:

Be it known that I, MATTHEW L. KING, a citizen of the United States, residing at Bradley, in the county of Kankakee and 5 State of Illinois, have invented a certain new and useful Silo-Door Frame, of which the following is a specification.

The object of my invention is to provide a silo door frame structure of simple, durable and inexpensive construction, so constructed and arranged that the door will accurately fit the door opening and provided with a smooth, firm edge for the door frame to fit against.

15 More particularly, it is my object to provide a cement door frame forming a continuous door opening in a silo, which frame is provided with a metal jamb having parts embedded in the masonry and designed to be secured to reinforcing rods or wires in 20 the silo wall, the cement portion of the door being so shaped and arranged as to be applicable to silo walls of any thickness by slight modifications.

25 A further object is to provide in such a device a double connecting bar, securing together the upright reinforcing means on each side of the door frame and provided with a spreader between the connecting 30 bars whereby any considerable longitudinal expansion of the bars is prevented, said bars being designed to permit considerable expansion of the silo wall but to prevent contraction thereof with relation to the 35 door opening.

40 My invention consists in the construction, combination and arrangement of the various parts of the device, whereby the objects contemplated are attained, as hereinafter more fully set forth, pointed out in my claims and 45 illustrated in the accompanying drawings, in which—

Figure 1 shows a front elevation of a part of a silo showing the door jamb or frame embodying my invention with parts of the door frame cut away.

Fig. 2 shows a horizontal, sectional view through the silo door frame and the door.

Fig. 3 shows a front elevation of the double connecting rod.

Fig. 4 shows a vertical, transverse sectional view taken on the line 4—4 of Fig. 1, and

Fig. 5 shows a side elevation of the metal 55 face of the door jamb showing the manner

in which the reinforcing wires are secured thereto.

In the accompanying drawings, I have used the reference numeral 10 to indicate generally the wall of a silo. The silo wall 60 10 is provided with a vertical continuous door opening. At each side of the opening is a jamb of peculiar construction, which forms part of my invention. This jamb is preferably made by means of molds made 65 according to my copending application for patent on forms for masonry structures, Serial No. 744,576, filed on 27 day of January, 1913.

The jamb comprises a frame or jamb 70 member 11, preferably made of cement and forming an extension of the silo wall 10. The cement jamb member 11 is preferably provided with a vertical air space 12, extending approximately from the upper to 75 the lower end thereof. The adjacent faces of the jamb member 11 are beveled from the outside of the silo wall inwardly and away from each other, as shown in Fig. 2. In each side of the jamb, I mount a T iron 80 14 with the top of the iron resting against the beveled portion of the jamb and with the shank of the T extending into the masonry portion 11 of the jamb. The T iron is provided with a plurality of openings 85 13 in the shank. To the openings 13 are secured reinforcing rods or wires 15. In the outer surface of the masonry or cement portion 11 is cut opposite vertical notches 16 extending from the top to the bottom of 90 the jamb. The tendency of the reinforcing rods 15, as will be seen from the drawings, is to draw the shank of the T iron 14 to position substantially parallel to said reinforcing rods. To counteract this tendency, 95 I provide a connecting rod 17 having hook members 18 at each end designed to extend over and engage the shank of the T iron and to be embedded in the masonry 11, as shown in Fig. 2. Over its central portion, 100 the rod 17 is divided into two parts, 17^a and 17^b, spaced apart from each other, and in the middle of the portions 17^a and 17^b I provide a spreader bar 19^a. The bar 17 serves several purposes. It counteracts the 105 tendency of the reinforcing rods 15 to pull the T irons away from their proper position, and also holds the T irons at a proper distance from each other, whenever the walls of the silo contract. On account of 110

the spreader bar 19^a, the distance between the hook members 18 remains approximately the same at all times, excepting for the slight expansion of the parts of the rod 17.

5 The rod 17 is preferably made of resilient material so that when the silo wall expands, the portions 17^a and 17^b on each side of the spreader bar 19^a may be bent outwardly. The advantage of this device will be herein-
10 after more fully explained.

Between the faces of the T iron 14, I place door sections 19 having beveled side edges to fit the faces of said T irons. On the outer side of each door section are a plurality of 15 sliding catch members 20 designed to slide laterally and enter the notch or groove 16 when the door sections are placed in position and to be held by the T-irons.

The advantages of my improved silo door 20 construction are numerous. By making the portion 11 of cement or other similar material, it can be made of any desired width and thickness so that it may be readily used in connection with silo walls of any thickness. By the use of the T irons 14 or similar 25 devices, I am able to provide a perfectly smooth beveled edge door jamb to receive the door sections 19. By means of the connecting rod 17, I hold the T irons 14 30 against spreading to a distance farther apart than the width of the door section 19. The door sections 19 are therefore always wide enough to fit the door.

On the other hand, should the silo wall 35 expand, the resiliency of the portions 17^a and 17^b is such as to permit them to bend and such expansion may take place without any breaks or cracks in parts of the silo.

The reinforcing rods 15 and the rod 17 40 counteract the effect of each other so that there is no undue strain on the T irons 14. On account of the smooth metal surface of the T irons and the means for holding the T irons in proper position, I am always able 45 to get a tight joint between the door sections 19 and the sides of the door jamb.

I claim as my invention:

1. In a silo, having a door opening, jamb members of plastic material at the sides of 50 said opening having beveled faces, to permit the door to be received in said opening with its inner surface substantially flush with the inner surface of the silo wall, and so that pressure from within will force the 55 door toward said faces, upright T-irons each

having a flange forming a beveled face protecting one of said first beveled faces, braces extended across the door opening substantially flush with the outer part of the opening, having portions embedded in said jamb 60 members and secured to said embedded flanges of the T-irons, said plastic material jambs having vertical notches at their outer edges to receive locking bolts or the like, and for permitting said bolts to engage said T- 65 irons.

2. In a silo, having a door opening, jamb members of plastic material at the sides of said opening having beveled faces, to permit the door to be received in said opening with 70 its inner surface substantially flush with the inner surface of the silo wall, and so that pressure from within will force the door toward said faces, upright T-irons each having a flange forming a beveled face to protect one of said first beveled faces, braces extended across the door opening substantially flush with the outer part of the opening, having portions embedded in said jamb members, and secured to said embedded 75 flanges of the T-irons, said plastic material jambs having vertical notches at their outer edges to receive locking bolts or the like, and for permitting said bolts to engage said T-irons, and a door having beveled side 80 edges, said door being provided on its forward surface with sliding locking bolts for entering said notches.

3. In a device of the class described, the combination of a silo, having walls provided 90 with a door opening, jambs of plastic material arranged at the sides of said openings provided with beveled faces, T-irons arranged with their central flanges projecting 95 into said plastic material jambs, each having a flange resting against and protecting one of said first named beveled faces, braces extending across said opening substantially flush with the outer portion of said opening having their ends projecting into said jambs, 100 a groove receiving the edges of said central flanges, and reinforcing means secured to said central flanges and extending into said walls.

Des Moines, Iowa, December 5, 1912.

MATTHEW L. KING.
